Primary Examiner — Robin V Webster*(74) Attorney, Agent, or Firm* — Morris, Manning & Martin, LLP; Daniel E. Sineway, Esq.; Bryan D. Stewart, Esq.(57) **CLAIM**

The ornamental design for the container with integrated handles, as shown and described.

DESCRIPTION

FIG. 1 is a perspective view of a container with integrated handles showing our new design;

FIG. 2 is a front view thereof;

FIG. 3 is a side view thereof;

FIG. 4 is a perspective bottom view thereof;

FIG. 5 is a top view thereof; and,

FIG. 6 is a bottom view thereof.
